UNITED STATES PATENT OFFICE.

JOHN F. O'CONNOR, OF CHICAGO, ILLINOIS, ASSIGNOR, BY MESNE ASSIGNMENTS, TO
W. H. MINER, INC., A CORPORATION OF DELAWARE.

ANTIFRICTION BEARING.

Application filed November 19, 1923. Serial No. 675,449.

This invention relates to improvements in anti-friction bearings.

One object of the invention is to provide an anti-friction side bearing for railway cars so designed as to possess unusual strength, whereby it is especially adapted for heavy service.

More specifically an object of the invention is to provide a bearing of the character indicated, adapted to be attached to the truck bolster of a railway car, as a unit, wherein a sliding upper bearing plate which directly engages the anti-friction element is adapted to coact with the body bolster, thereby by eliminating the usual tempered steel facing on the body bolster.

A still further object of the invention is to provide a side bearing of the character indicated, wherein simple, efficient and reliable means is provided for returning the anti-friction element to centered position after each actuation of the bearing.

Other objects and advantages of the invention will more clearly appear from the description and claims hereinafter following.

In the drawing forming a part of this specification, Figure 1 is a vertical, sectional view taken parallel to the length of the car, through the ends of the body and truck bolsters and showing my improvements in connection therewith. Figure 2 is a top plan view of the bearing shown in Figure 1. And Figure 3 is a vertical, sectional view corresponding substantially to the line 3—3 of Figure 1.

In said drawing, 10 indicates the under-side of a body bolster of a railway car and 11 the upper side of an opposed truck bolster. In the instance shown, the improved side bearing is applied to the truck bolster.

The improved bearing comprises, broadly, a housing or retaining member A; a bottom bearing plate B; an anti-friction element C; a sliding upper wear plate D; a pair of centering springs E—E; two pairs of spring follower thimbles F—F; and a pair of retaining elements G—G.

The retaining member A, as shown, is of generally box-like form, having a bottom wall 12, vertically disposed, spaced side walls 13—13, vertically disposed, spaced end walls 14—14 and a pair of lugs or ears 15—15, one at each end, by which the retaining member is adapted to be riveted or otherwise rigidly secured to the upper surface of the truck

bolster. At the upper end, each side wall 13 is offset outwardly, thereby providing a pair of pockets 16—16, one at each side of the member A, extending longitudinally of the same.

The bottom bearing plate B is of substantially rectangular outline and has an upper face, curved longitudinally of the housing on an arc of relatively great radius as indicated at 17. The under face of the plate is flat and bears directly on the bottom wall 12 of the housing. The plate B extends from one side wall to the other and has the two remaining edges equally spaced respectively from the end walls of the housing, as clearly shown in Figure 1. To prevent displacement of the plate B lengthwise of the housing, the former is preferably provided with a pair of depending, spaced, central lugs 18—18 engaging within suitable openings 19—19 formed in the bottom wall 12. Adjacent each side wall, the plate B is provided with a pair of upstanding knobs or teeth 19—19 adapted to engage within corresponding openings 20—20 formed in the bottom of the anti-friction element C to thereby prevent the latter from being shifted bodily with respect to the housing A.

The anti-friction element proper C is in the form of a rolling rocker and is formed with cylindric top and bottom bearing surfaces 21 and 22, adapted to coact respectively with the plates B and D. The bearing surfaces 21 and 22 are preferably curved on arcs of equal lengths and of relatively long radius.

The sliding plate D is also of substantially rectangular form and presents a spherical upper surface 23 of very long radius, adapted to coact with the under-surface of the body bolster 10.

By the provision of the upper side with a spherical upper surface adapted to engage with the flat under-surface of the truck bolster, deviations from the parallel relation of the opposed faces of the body and truck bolster, due to varying conditions in service which may occur from wearing of the parts or distortion of the bolster, are taken care of and a central contact between the anti-friction element and the coacting bearing surface is at all times assured. In other words, if the under-surface of the body bolster is disposed angularly with reference to the upper bearing surface of 110

the truck bolster, the body bolster will contact with and exert pressure on the upper sliding wear plate approximately at the center or at a point closely adjacent the center 5 of the plate and the force will act substantially through the center of the anti-friction element. It will be evident that by forming the plate with an upper surface of spherical form, proper contact of the body bolster 10 therewith is assured and very simple and efficient means is provided for taking care of angularity between the opposed bearing surfaces of the body and truck bolsters. This means replaces the more complicated 15 mechanism now generally used involving the mounting of the anti-friction element in a cradle or on a corresponding additional element pivotally mounted within the base casting or retaining member directly secured 20 to the bolster.

The under-surface 24 of the plate D contacts with the surface 21 of the anti-friction element and is also curved longitudinally of the housing on an arc of relatively long 25 radius, the curvature being preferably the same as that of the bottom plate B. Adjacent each side wall 13 of the housing, the plate D is reduced in thickness as clearly shown in Figure 3, thereby providing a 30 flange 25 extending over the corresponding pocket 16 and over-haging the side wall of the pocket. Adjacent each end of the roller, the plate D is provided with a pair of depending knobs or teeth 26—26 adapted to 35 engage within corresponding openings 27—27 provided in the top of the anti-friction element C to control the movement of the latter and effect return of the same to centered position with the plate D. The plate 40 D is also provided with a pair of spaced ears 28 depending from each flange 25, disposed transversely of the housing and extending into the corresponding pocket 16. The ears 28 of each pair are disposed adjacent the opposite ends of each flange; and each of the same is provided with a horizontal, outwardly opening slot 29 adapted 45 to accommodate the cylindrical body portion of the corresponding thimble F.

50 The thimbles F are of like construction and arranged in pairs at opposite sides of the housing. Each thimble F includes a relatively long, hollow, cylindrical body portion closed at its outer end and provided 55 at its inner end with an annular flange 30. Each thimble extends through the slot in the corresponding ear 28 and has the flange 30 engaging the inner side of the ear. The outer end of each thimble is adapted to abut 60 the corresponding end of the housing, when the parts are in normal position.

65 One of the springs E is arranged at each side of the bearing and has its opposite ends disposed in the respective thimbles bearing on the closed end walls thereof and holding

the same in yielding contact with the end walls of the housing, when the parts are in normal position. The parts are so proportioned and arranged that the flanges 30 of the respective thimbles engage the corresponding ears of the slide D when the outer end of the thimbles are in abutment with the end walls of the housing, thus retaining the slide in centered position.

70 The retaining elements G are in the form of rods, one being disposed at each side of the housing, extending through the corresponding spring E, aligned openings in the thimbles F and the end walls of the housing, the opposite ends of the rod being headed over to retain the same in position. It will 75 be evident that when the parts are assembled with the rods in fixed position, the slide plate D will also be retained in assembled relation with the housing thereby, and in 80 turn retain the anti-friction element within the housing.

85 By the construction and arrangement described, I provide a side bearing having an anti-friction rocking element that has arcs 90 of unusually large radius, and wherein the over-all height of the bearing is maintained substantially constant during the entire operation of the safe, by providing bearing surfaces of the proper curvature on the top 95 and bottom wear plates.

100 The top and bottom wear plates and the anti-friction element therebetween may be made of any suitable material but are preferably constructed of steel and properly tempered.

105 The normal position of the parts is as shown by the full lines in Figure 1. In this position, it is evident that the sliding plate D is supported slightly below the under surface of the body bolster. It will be seen that upon approach of the body and truck bolsters toward each other, the spherical, upper surface of the plate D will be engaged by 110 the body bolster and the pressure thereon properly centralized due to the formation of the upper surface of the plate. When the bearing is brought into action by the relative radial movement and approach of the body and truck bolsters, the slide D will be moved 115 relatively to the housing and the element C rolled to either side of normal, as for instance, to the position indicated by the dotted lines in Figure 1. It will be evident that the rolling movement of the anti-friction element C will be at all times positively controlled by the knobs 26 engaging the recesses at the upper side of the element and the knobs 19 engaging within the recesses 120 at the bottom side of the same. The limit of the movement of the anti-friction element is reached when the same reaches the dotted line position shown in Figure 1. As the slide moves to the dotted line position, the thimbles at the right hand side of the bear- 125

130

ing, as shown in Figures 1 and 2, will be moved therewith by engagement of the ears 28 of the former with the flanges 30 of the latter, thereby compressing the springs E. 5 When the pressure on the bearing is removed, the slide D will return to normal position under the influence of the springs E through the medium of the thimbles F. The 10 slide, in turn, effects return movement of the anti-friction element to properly centered position.

I have herein shown and described what I now consider the preferred manner of carrying out my invention but the same is merely 15 illustrative and I contemplate all changes and modifications that come within the scope of the claims appended hereto.

I claim:

1. In a side bearing, the combination with 20 a supporting wear plate fixed to the truck bolster and having an upper curved bearing surface; of an anti-friction element having rocking movement on said wear plate; inter-engaging means on said plate and ele- 25 ment for controlling the rocking movement of the latter; a slide supported upon said element and having a bottom face adapted to coact with said element, the slide being

normally free of engagement with the body bolster, but adapted to be moved to actuate 30 said element by engagement with the body bolster; coacting means on said slide and element for effecting return movement of the element to normal position and controlling the rocking action of said element during 35 the return movement; and means for returning said slide to normal position after each actuation of the bearing.

2. In a side bearing for railway cars, the combination with a housing adapted to be 40 secured to the truck bolster of a railway car; of an anti-friction element within the housing; a slide resting upon said element and adapted to be engaged by the body bolster, said slide having lugs extending into 45 the housing; a thimble extending through each lug and adapted to be moved therewith in one direction; spring means for holding said thimbles normally separated; and re- 50 tainer rods extending through said thimbles and adapted to hold all parts of said bearing assembled.

In witness that I claim the foregoing I have hereunto subscribed my name this 13th day of November, 1923.

JOHN F. O'CONNOR.
